UNITED STATES PATENT OFFICE.

FRANZ BURGERS, OF GELSENKIRCHEN, GERMANY.

PROCESS OF TREATING AND REFINING CRUDE IRON.

Application filed March 12, 1925. Serial No. 14,969.

To all whom it may concern:

Be it known that I, FRANZ BURGERS, a citizen of the German Republic, and resident of Gelsenkirchen, Germany, have invented ⁶⁰ certain new and useful Improvements in a Process of Treating and Refining Crude Iron, of which the following is a specification.

The present invention relates to certain ¹⁰ improvements upon the process for treating and refining crude iron as disclosed in my prior application, Serial No. 723,524.

In my prior application there is described a process of refining crude iron which ¹⁵ involves the introduction into a furnace charged with coke or other combustibles of a liquid supply of crude iron. The liquid pig iron was introduced thru the side of the furnace by an inlet trough provided with a ²⁰ number of branches at its discharge end by which the iron was immediately distributed over the entire furnace area or by a trough surrounding the furnace wall and discharging the iron into the furnace thru radial inlets, the molten iron being thereby splashed ²⁵ so to speak, over the whole bed of incandescent coke and trickling down thru the fuel bed underwent the well known refining process common to the remelting of pig iron in ³⁰ the making of ordinary foundry iron. It has been found that some objectionable results follow from this practice of delivering the iron onto the fuel bed.

In my present invention the molten pig ³⁵ iron is introduced by suitable means to the center of the incandescent fuel bed and descends from this center delivery point in a diverging cone-like stream until it is distributed uniformly thru the furnace.

The invention further relates to certain ⁴⁰ furnace constructions for facilitating the carrying out of the above described process.

In the accompanying drawings—

Figure 1 represents a vertical cross-section ⁴⁵ of a furnace embodying my invention; and Figure 2 is a similar section of a modified form thereof.

The furnace 1 is of the ordinary cupola type and has applied to it at a suitable elevation ⁵⁰ a sliding trough 2 whereby the molten contents of a ladle 3 may be introduced into the middle of the furnace. The trough may be made removable as shown by the dotted lines. The molten crude iron will ⁵⁵ thus be directed to the very center of the in-

candescent fuel and will only gradually distribute itself thru the fuel bed descending in the form of a cone until it becomes uniformly and symmetrically distributed. The trough may be provided with an inclined chute 4 for supplying the fuel which introduced at the mouth of the chute will descend into the furnace only so fast as it is consumed therein, thus maintaining the incandescent depth of the fuel constant. ⁶⁵

In Figure 2 a modification is shown wherein the upper part of the furnace is built on an angle and the liquid iron introduced at a point on the upper side of the inclined portion at an elevation which will ⁷⁰ cause the iron in descending in a cone-like stream to distribute itself gradually and uniformly thru the fuel bed. The point at which the fuel is introduced should bear such a relation to the point at which the molten ⁷⁵ pig iron enters the furnace, that the coke while being preheated in this intermediate space will, however, not be raised to the combustion point as obviously any fuel burning above the point of introduction of ⁸⁰ the metal will have no useful effect.

Other shapes of furnace may be employed providing the principles involved in the invention are adhered to namely, the introduction of the fluid iron at a point where ⁸⁵ it will descend in a diverging cone-like stream until it is distributed uniformly thru the incandescent fuel bed.

I claim:

1. A process for refining crude iron comprising, introducing fuel into a furnace through a chute, preheating the fuel by the gases arising from the burning fuel, melting the crude iron in a separate furnace conveying the molten metal to the refining fur- ⁹⁰ nace and introducing the molten iron at a point near the vertical axis of said furnace and below the upper limit of incandescence. ⁹⁵

2. A furnace for treating crude iron comprising in combination, furnace walls for enclosing an incandescent body of fuel, an inclined chute for conveying the fuel into the furnace from the side, the fuel in the chute descending only as the fuel in the furnace ceases to support it and means for introducing molten crude iron at the central axis of the furnace and at a point where the fuel becomes incandescent. ¹⁰⁰ ¹⁰⁵

FRANZ BURGERS.
